UNITED STATES PATENT OFFICE.

HERON S. CURTIS, OF NORTH ATTLEBORO, MASSACHUSETTS, ASSIGNOR TO T. I. SMITH COMPANY, OF NORTH ATTLEBORO, MASSACHUSETTS, A TRUST ASSOCIATION OF MASSACHUSETTS.

BUCKLE.

Application filed August 13, 1921. Serial No. 491,931.

To all whom it may concern:

Be it known that I, HERON S. CURTIS, a citizen of the United States, and resident of North Attleboro, in the county of Bristol and State of Massachusetts, have invented certain new and useful Improvements in Buckles, of which the following is a specification.

This invention relates to buckles for belts and other purposes and is intended to provide a buckle of the tongueless type requiring no perforation of the belt for tongue receiving holes which shall be capable of an indefinite range of adjustment of the strap or belt while at all times affording a reliable grip to hold the belt at any desired position of adjustment and at the same time perfectly accommodating itself to the different thickness of different belts.

Tongueless buckles with clamping rollers have heretofore been used with a considerable measure of success but it often happens when thin stock of soft metal like sterling silver is used in this class of buckles the pressure of the belt upon the roller journals transmitted to the thin edges of the slots in the side flanges of the buckle body produces rapid wearing away or impression of such edges at the points of pressure so that recesses are formed into which the roller journals sink thus interfering with the proper action of the roller in relation to the belt and weakening the grip of the roller against the belt whereby the belt is allowed to slip. Moreover the slotting of the side flanges tends, particularly when thin stock is used, to weaken the flanges so that they are easily bent or deformed.

The present invention overcomes these difficulties by providing a clamping member with a sufficiently broad bearing contact against the buckle so that the gouging or cutting of the guide portion of the buckle is prevented while at the same time, the side flanges instead of being weakened by slots are actually strengthened by flanges which form both guides for the clamping member and stiffening means for reinforcing the buckle body.

In general the invention comprises a front or body plate provided with parallel side flanges having their inside edges inturned toward each other to form guides or tracks on which the clamping member is slidably

supported, stops being provided to limit the movement of the clamping member or slide and to prevent its accidental detachment from the body of the buckle.

This and other features of the invention will be explained on the following specification and will be defined in the claims hereto annexed.

In the accompanying drawings is illustrated a convenient and simple form of device embodying the principles of their invention, in which;

Figure 1 is a front elevation of the buckle as it appears when in use on the person.

Figure 2 is a side view thereof as seen from above.

Figure 3 is a longitudinal central section showing the clamping member or slide in belt gripping position.

Figure 4 is a transverse central section showing the same.

In the practice of the invention according to the specific form thereof shown in the drawings, I employ a body member comprising a front plate *a* having rearwardly or inwardly turned flanges *b* extending in parallelism along opposite sides of the front plate.

At one end of the buckle the side flanges are perforate or counter sunk to form a pair of aligned bearings for the ends of a swinging or pivotal bail *c* to which the anchored end of the belt or strap *d* is secured in any suitable manner.

Adjacent to the anchorage or bail carrying end the side flanges *b* have their edge portions *e* turned in toward each other to form stiffening flanges. On the other side of the middle of the buckle the side flanges are also turned inward toward each other to form flanges or lips *f* which not only act to stiffen the buckle body and particularly the flanges *b* but which also are inclined at an acute angle to the front plate of the buckle lengthwise thereof so as to form oblique guides or tracks which gradually approach to the front plate near the end thereof so as to form inclined parallel tracks in the same plane.

As indicated in Figures 1 and 3 these tracks or guides are formed at their outer ends with inward projections *g* which form stops at the end of the buckle. At their ends near the middle of the buckle a portion

of each guide f is turned toward the front plate or outwardly to form stops o to limit the movement of the clamping member in that direction.

- 5 The clamping member or slide is preferably formed of a single piece of metal and comprises a flat bearing plate or strip h of sufficient length to project beyond the side flanges of the buckle and one or more forwardly turned or projecting lips i of sufficient depth to grip a fairly thin belt when the slide is near the adjacent end of the buckle and to grip a fairly thick belt when the slide or clamping member is near the middle of the buckle.

As shown in Figure 4 the opposite ends of the gripping portion or lip i is under cut of slotted, immediately adjacent to the main or bearing plate h of the slide so as to engage and receive the guide flange f on that side. Thus it will be understood the cross bar h has a flat sliding contact or bearing with the rear faces of the guides f , while the slotted or under cut gripping lips or members i receive the thrust or pressure to cause the clamping of the belt between the front plate and the slide or clamping member.

In assembling the device, the stops or lips o will not be bent up until after the clamping member has been inserted and pushed along beyond the position occupied by the lip portion o ; then the lips can be bent to form stops and the travel of the slide h is limited by the outer stops g and the inner stops o so that the slide or gripper cannot fall off or separate from the buckle.

In practice the fixed end of the belt d is looped around or otherwise secured to the anchorage member or bail, while the tongue or free end of the belt is inserted and pushed through the buckle between the front plate and the movable clamp which, in order to afford ample clearance is pushed back toward the middle of the buckle. When the belt is drawn through to the desired adjustment, the clamp is moved toward the buckle end opposite the anchorage member until by its approach toward the front plate it grips the belt and pinches it against the front plate. In this position any pull tending to draw the tongue or free end of the belt out of the buckle acts to cause a tighter grip by the clamp by reason of the inclination of its guide tracks toward the front plate. A forward pull on the tongue end tends to relax the grip on the belt since it tends to draw the clamp toward the middle of the buckle. This makes it very easy to release and take off the belt.

The clamping or belt gripping member has a wide bearing engagement with the buckle body and presents a very effective gripping edge to press against the belt

thereby minimizing the tendency of the belt to slip under strain. Moreover this gripping edge can be easily made of a curvature or contour corresponding to the transverse curvature of the front plate when the front plate is "crowned" so as to grip the belt through its whole width.

While I have shown a pivoted bail for an anchorage it will be understood that any suitable means for securing or retaining the anchored end of the belt may be used.

What I claim is:

1. In a belt buckle, the combination of a front plate having rearwardly projecting side flanges whose edge portions are in-turned to form guide ledges inclined to the front plate, a clamping member comprising a U-shaped transverse plate arranged to extend transversely across the guide ledges and form interlocking and sliding engagement therewith to cause the two edges to crowd into the free end of the belt when inserted between the clamping member and the front plate, said ledges being provided at their opposite ends with projecting lips arranged to prevent the withdrawal from the ledges of the transverse clamping member, and means affording an anchorage for the fixed end of the belt, substantially as described.

2. In a belt buckle, the combination of a front plate having rearwardly projecting side flanges whose edge portions are in-turned toward each other to form inclined guide ledges, a transverse clamping member comprising a flat plate arranged to extend across and project beyond the guide ledges and having in-turned flanges arranged to form gripping engagement to pinch the interposed belt against the front plate, said flanges being slotted in the direction of their length to receive and interlock with said inclined guide ledges, and means affording a self-adjusting anchorage for the fixed end of the belt, substantially as described.

3. In a belt buckle, the combination of a front plate having rearwardly projecting side flanges provided with inwardly projecting guide tracks inclined forwardly from the middle to the end of the buckle, a slidably clamping member of U-shaped cross-section whose opposite ends are slotted to form track-receiving grooves which maintain the strap-clamping edges of the U-shaped clamping member in parallelism as the clamping member moves along the tracks to grip the strap adjustably against the front plate, and means for retaining the fixed end of the strap, substantially as described.

In witness whereof I have subscribed the above specification.

HERON S. CURTIS.
